UNITED STATES PATENT OFFICE.

GEORGE LITINSKY, OF ELKINS, WEST VIRGINIA.

OVEN OR FURNACE FOR BAKING EARTHENWARE.

1,265,097.

Specification of Letters Patent.

Patented May 7, 1918.

Application filed July 1, 1916. Serial No. 107,212.

To all whom it may concern:

Be it known that I, GEORGE LITINSKY, a subject of the Czar of Russia, residing at Elkins, in the county of Randolph and State 5 of West Virginia, have invented certain new and useful Improvements in Ovens or Furnaces for Baking Earthenware, of which the following is a specification, reference being had therein to the accompanying drawing.

10 This invention relates to an improvement in furnaces or ovens for treating earthen materials that require high heating, such as pottery, porcelain, bricks, and the like. The object of the invention is to provide an oven 15 structure for work in this class which will accomplish a desired amount of work, with great economy in fuel, and also lessen the time required for baking, burning, or calcining.

20 In the drawings—

Figure 1 is a vertical section of a furnace or kiln embodying my improvements; taken on the line 1—1, Fig. 4.

25 Figs. 2 to 7, inclusive, are sections on horizontal planes through the structure in Fig. 1, they being taken, respectively, on the lines A, B—C, D—E, F—G, H—I, J— and K, L.

30 In the construction shown there are three chambers, M, M', M'', in a vertical series, each inclosed by a circular wall and a dome-shaped ceiling or roof. They are formed in a refractory masonry structure, the upper 35 body of which is built up of brick, as at 21, with casings or linings of fire brick, as at 22, at all surfaces where flames and hot bodies contact. 20 is a foundation resting upon the hearth mass 23. The cylindrical wall 13^a is carried upward from the foundation to 40 the top of the structure. In its base portion are constructed a series of furnaces extending somewhat beyond the wall, and each having a fire box 1, an ash pit 1^a with the grate at 1^b, the door at 1^c for regulating draft 45 and removing ashes, the fuel supply passage 1^d adapted to be closed by a stopper 1^e, a water holder 1^f, and a door 1^g for controlling the air above the grate. Outside of the 50 furnace, proper, there is a receptacle 24 with which the ash exit of the furnace communicates.

55 The flues 16^a from the lower furnaces extend up to large openings 16^d in the vertical wall of the lower oven M. The back wall 16^e of each flue 16^a inclines inward and intersects the wall 25 of the oven at the line

16^f, and a large part of the flame and combustion gases are carried, without resistance, up to the curved surface of the ceiling dome which causes them to be evenly distributed 60 over the area of the oven, and part goes directly inward and downward.

26 is a doorway in the wall of the oven through which operatives can pass for introducing articles to be treated, and with- 65 drawing them. During the period of operation, this is closed by a fireproof brick closure. 7 is the floor of the bottom oven, see Fig. 5. It is formed of fire brick and is provided with a series of sets of gas aper- 70 tures peculiarly related to insure complete uniformity in heat distribution. Those of the several sets are respectively indicated by 7^b, 7^c, 7^d, and, as here shown, there is a single central aperture 7^e. The apertures of 75 each of these sets are uniformly distributed over a predetermined annular part of the total horizontal area of the floor. The lines defining these are approximately indicated by the dotted circles in Fig. 5. The outer- 80 most annulus is that at 7, the next at 7^e, the next at 7^b, and the innermost, virtually a circle, at 7^c. The ratio of the total area of the apertures 7^e to the total area of the annulus 7^c is less than the ratio of the total 85 area of the apertures in the next section 7^e of the floor to the total area of that section. The ratio of the area of the apertures to the annular area of the second section is less than the corresponding ratio in the third 90 section, and the ratio between the central apertures 7^e and of the inner circle 7^c is greater than any of the other ratios.

I have related the apertures and the different parts of the bottom 7 of the oven M 95 in the way just described in order to insure practically perfect distribution of the downwardly moving volumes of gases which are received from the furnaces through the flues 16^a. The peculiar structure and relationship of parts in the base of the oven will be understood by comparing the vertical sections in Fig. 1 with the horizontal sections in Figs. 2, 3 and 4.

In the main vertical walls 13^a of the structure there are formed vertical flues 13 and 13^b, each being on vertical lines midway of the vertical lines of two of the adjacent furnaces above described. Twelve furnaces are shown with twelve intervening spaces (as 110 seen in horizontal section). There are nine of the vertical flues 13 and two larger ones

13^b, one of the intervening spaces between the furnace chambers (to wit, that in the vertical lines of the doorway 26) lacking a flue. But the two terminal flues of the circular series, those at 13^b, have a cross area equal to the cross area of three of the flues 13, so that the total area of the vertical flues for uprising gases is equal to the total area of the inlet flues 16^a, each of the latter being, in area, equal to one of the flues 13.

The flues 13 and 13^b, at their lower ends, communicate with horizontal ducts 12 which, in turn, communicate with a horizontal annular duct 12^a in the lower planes of the oven's bottom structure (see Figs. 1 and 2). 11 and 11^a are parallel, horizontal, annular ducts in the horizontal planes of the inner duct 12^a. At the center of this bottom structure of the oven there is a pillar 10^b. 10, 10^a, are ducts leading from the inner, annular duct 11 to the second one at 11^a. 10^a, 10^b, are horizontal ducts leading from the annular duct 11^a to that at 12^a.

Immediately above this system of ducts 25 (10, 11, 11^a, 10^a, 12^a) there is a refractory horizontal wall with perforations, as will be understood on referring to Fig. 3. In this are ducts 9, 9^a, 9^b.

And in horizontal planes above these 30 ducts 9, 9^a, 9^b the refractory material of the bottom is provided with a series of ducts 8, 8^a, 8^b, 8^c, in four series. The gases passing through the central aperture 7^e move radially outward through the ducts 8^a, Fig. 4, 35 then down through the tapering ducts 8^e to the annular duct 11. Those which pass through the apertures 7^d first travel radially outward through the ducts 8, then down through apertures to, and radially inward 40 along, the ducts 9, then downward into the annular duct 11, and thence outward through 10, 11^a, 10^a, 12^a, 12 and 13. The gases which pass vertically through the apertures 7^b enter the ducts 8^b and travel radially inward, 45 then through vertical apertures to and along the ducts 9^b, then down into the annular channel 11^a, thence through 10^a, 12^a, 12 and 13.

Those which pass downward through the 50 apertures of the outermost series 7^b enter, and travel radially inward along, the ducts 8^c, thence down through apertures into, and radially outward along, the ducts 9^b, thence down into the annular channel 12^a, and 55 thence through 12 to 13.

The second oven chamber M' has a vertical, refractory wall casing and dome of fire brick. For this oven there are also provided furnaces, each having a fire box 4, an ash pit 60 4^a, a duct or flue 5, and an inlet opening 5^a communicating with the interior of the oven.

The upper part of the flue 5 is inclined, as above set forth, when describing the flue 16^a, and for the purpose set forth. The inner 65 wall 5^b of the flue 5 is inset relatively to the

circular plan of the chamber, as seen in Figs. 1 and 6. A doorway at 27 is provided for introducing articles to the chamber and for withdrawing them. At 3^b there is a duct or passage leading through the top at the center of the oven chamber M'. This, when desired, can be closed by a refractory closure, such as a layer of fire brick; and when not required, these can be removed.

The bottom or floor 6^a of this second oven 75 chamber M' is provided with apertures or passageways, as shown in Figs. 1 and 6. Here, also, the apertures are in several sets, and those of each set are arranged in predetermined relation to a certain annular part 80 of the area of the circle of the floor. The boundaries (between the periphery 6^a and the center) of these annular sections of the floor area are indicated by the dotted arcs at 6^b and 6^c. The ratio between the total area 85 of the apertures 6^b and the area of the outermost annulus is less than the ratio of the total area of the apertures 6^c to the area of the second annulus, and the ratio between the area of the apertures 6^c and that of the second annulus is less than the ratio between the area of the central aperture 6^d and the area of the innermost annulus. Consequently, the streams of gases moving downward from the ceiling dome of this second oven M' are 90 uniformly distributed over the whole horizontal area of the chamber. The incoming streams of gas bring in uniform amounts of heat, as the furnaces 4, 4^a are uniformly distributed in relatively large numbers around the periphery of the oven, and the volumes of heat-carrying gases are caused to enter the upper part of the chamber with a substantially uniform distribution over the area of the top of the oven because of the peculiar 95 arrangement of the upper ends of the flues 5. And this uniform distribution across the horizontal area is maintained even across the lowermost horizontal planes of the chamber because of the peculiar relative arrangement of the several sets of escape apertures 6^b, 6^c, 6^d, as above described.

These exit apertures in the bottom of the second oven M' may be closed by fire brick; or other suitable closure, when desired, as, 115 for example, in case it should be desired to use the lower oven M for any purpose, and the further desire to avoid the passage of any heat-carrying gases upward through the flues 6^b, 6^c, 6^d. Ordinarily, however, the 120 apertures or flues last specified are left continuously open.

The furnace at 4, 4^a is provided with doors 4^b for introducing fuel, and for controlling or stopping the entrance of air above the 125 grate, and with a door at 4^c to control the entrance of air below the grate, and also to permit the removal of ashes or trash from the ash box 4^a to the receptacle at 4^d. A body of water is introduced at 4^e in the ash 130

chamber, either by inserting the vessel containing the water or by introducing it directly to the chamber.

The flues 13, 13^b, at their upper ends, communicate with horizontal ducts 13^c that extend radially inward below the uppermost oven chambers M². 14, 14^b, 14^c are apertures in the floor 28 of this chamber, three apertures for each of the flues 13^c. These apertures or openings are in sets, those of each set differing in size from those of the others, and being at distances from the center varying from the distances of those in the other sets for the purpose of uniformly distributing the heat-carrying gases that rise through the flues 13, 13^b toward this oven M². 29 is a doorway permitting the passage of operatives into and from this oven which, like the doors 26 and 27, can be closed by a removable brick wall when required.

From this uppermost oven chamber the gases finally escape through the stack 15 to the open atmosphere.

A furnace or oven structure, such as above described, can be used as follows. Let it be assumed that common bricks, in their "green" state, are to be treated in charges containing equal numbers of thousands. Preliminarily, they have been molded and compressed, and still contain surplus moisture, together with their water of constitution or crystallization. They require a preliminary drying or expelling of surplus water, that is, the water which is present in excess of the water of constitution. Then they require excessively high heating to cause the various reactions and physical changes involved in burning, baking, or calcining.

Let it be further assumed that two of such charges have been preliminarily dried.

Thereupon, one of them is placed in the oven chamber M', the several bricks of the charge being disposed in any suitable way to permit the free access of the heat-carrying gases to them, and the free circulation of these through the mass.

A second charge is similarly disposed in the lower oven chamber M.

A third charge is placed in the upper chamber M², but these are "green" articles requiring the aforesaid preliminary drying.

Then the flue or aperture 3^b is closed by a refractory stopper. All the lower furnaces 1, 1^a are cold, or if they have been previously fired, they are completely shut off; the doors at 1^c and 1^d are closed, and the closure at 1^e is inserted.

Fires are started in the furnaces at 4 and 60 are brought up to their highest efficiency in combustion. The flames and products of combustion rise rapidly through the flues 5 and escape into the chamber M' through the passages 5^a. After being uniformly distributed at the top of the chamber M' over

its cross area, they are carried down in uniformly distributed streams through the mass of articles resting on the floor 6^a, and pass out from the chamber M' through the passages 6^b, 6^c, 6^d to the oven M below. The 70 firing in the furnace 4 is carried to such a high degree that, in due time, the articles in the chamber M' become white hot.

Soon those which are disposed in the oven M become red hot from the heat derived from the gases that escape downward from the second chamber M'. They maintain the articles in the chamber M at such red heat during the period determined for maintaining those in the chamber M' at 80 white heat.

After the gases have passed from the top to the bottom of the chamber M, they escape through the apertures 7^b, 7^c, 7^d, 7^e, to the zig-zag, tortuous passages in the refractory heat-conserving bottom structure. This abstracts a great part of the heat remaining in the gases after they leave the oven, but being still somewhat warm, they readily pass from the zig-zag and circular 90 ducts in the bottom structure to, and up through, the vertical ducts 13, 13^b. From these they escape through the apertures 14, 14^b, 14^c into the oven M² where they effect the preliminary drying of the "green" articles in the charge disposed therein. All of the parts of the apparatus, the oven chambers, the ducts, and the flues, are so related that only that quantity of heat is left in the gases at the time they rise in the flues 13, 100 13^b, which will be sufficient to produce the required draft through the stack 15 after they have finished the work of drying, or lifting the moisture away from, the "green" articles in the uppermost chamber.

The design of the parts in relation to each other is such that the following is an example of what can be accomplished:

If it requires twenty-four hours to thoroughly burn, bake, or calcine, the materials 110 of the charge at white heat in the second oven M, the surplus heat carried downward from this chamber to the oven M so acts during the said twenty-four hours upon the articles in the latter that they require only 115 twelve hours of white heat firing thereafter. And this is effected as follows:

After the treatment of the charge in the second chamber M' has been finished, the articles therein are allowed to cool. The 120 fire box 4 and the ash box 4^a are closed tightly, and all circulation of hot gases, through the flues 5, is stopped. Then the fires in the furnace at 1, 1^a, are started, or brought again into action. Fuel is supplied 125 through the feedways 1^d, and the valves or stoppers at 1^e are removed. The firing in these lower furnaces is raised until the articles in the lower chamber M (which, as above described, are at red heat) are brought to 130

white heat. And they are maintained at this temperature; but only for a period of twelve hours. During this period the currents of the heat-carrying gases will rise 5 through the flue 16^a and will be uniformly distributed over the area of the lower oven M. They pass down in contact with, and among, the articles therein stored, and finally escape through the apertures 7^b to 10 7^e in the bottom, and then, after traversing the zig-zag or tortuous passageways in the heat-abstracting bottom structure, escape through the flues 13, 13' to the drying chamber M².

15 The heat which is first absorbed by the mass of refractory material at and below the floor 7^a, and then again given off by it to the articles in the oven M, is found to be of the utmost importance in respect to economizing fuel. And under some circumstances, and in treating some articles, I use 20 the lower oven only, and by uniformly distributing the heat-carrying gases over the area of this oven and conserving the surplus 25 heat carried by them to the bottom, I can accomplish a given amount of work at much less expense of fuel and in much less time than those required for treating similar charges in single-oven furnaces.

30 But I prefer, in most instances, to combine with this bottom oven an apparatus such as the oven M' and its furnaces, separate from those connected to the lower oven.

The time required for cooling the articles 35 in the second oven M' is generally much longer than the time required for maintaining at white heat the articles in the lower oven M. That is, during the twelve hours that the articles in the lower oven are exposed to white heat, the articles in the upper oven are cooling to the point where they 40 can be removed.

The presence of the water in the ash chambers 1^a and 4^a are also matters of great 45 importance in respect to obtaining the greatest benefit from the fuel. The masses of material in small particles which are continually dropping, or are raked, through the grate bars and fall to the bottom of the 50 ash chamber, still contain burning carbon. And the accumulation often amounts to a large mass. It imparts high heat to the grate bars and is one of the factors that results in rapidly burning them out. Moreover, there is always more or less oxygen 55 present in the ash box, even when the doors are closed, and this uniting with the burning carbon often forms large volumes of carbon dioxid gas (CO₂). This envelops, 60 to a greater or less extent, the burning fuel on the grate and blankets it against the desired access of oxygen, lowers the combustion, and holds down the production of heat.

The bodies of water which I introduce 65 instantly extinguish the dropping particles

of flaming and slowly oxidizing carbon; absorbs their heat; and prevents the generating of carbon dioxid and other fire-smothering gases. In this way I am enabled to increase the intensity of the combustion 70 and the heat generation to a large extent, and hasten the burning and baking of the earthenware.

Important advantages result from the form and arrangement of the openings 16 through which the flames and hot gases pass 75 from the flues 5 and 16^a into the oven chambers. They can come out from the flues on horizontal and on downwardly inclined lines, and also come out in such way as to pass around, and turn down from, the dome ceilings. Consequently, I can practically fill the chambers completely full with articles to be treated, this being in contradistinction from the arrangements of the parts 85 of ovens heretofore used which necessitated the leaving of large open spaces between the tops of the piles of articles and the dome ceilings.

The drawings illustrate the important fact 90 that there is a predetermined relationship between the cross areas of each aperture 7^b, 7^c, 7^d, 7^e and the cross areas of the ducts in the bottom structure. For example, it will be seen that the cross area of the aperture 7^b is less than the cross area of the duct 8^c with which it communicates; that the area of this duct is less than the duct 9^b in the series; and that this, in turn, is less than that of the annular duct 12^a. That 95 is to say, the gas which undertakes to enter through a series of ducts through an aperture 7^d is slightly resistant and is furnished a passageway which continually expands. This relationship of areas is predetermined 100 for the purpose of permitting the abstraction of as much heat as can be withdrawn without interfering with the draft, and, on the other hand, permitting the gases to pass 105 through without abstraction.

As above noted, when the articles in chamber M are being heated to white heat, those in chamber M² are being allowed to cool off, and much of the heat from chamber M', during the cooling stage, is received 115 in chamber M and assists in the treatment of the articles therein.

At times when the articles in both chambers M' and M are being allowed to cool, the closure at 3^b can be opened and the 120 heat from the ovens M and M' can be allowed to pass upward through the opening at 3^b, and this heat further assists in the drying of the "green" articles that are being preliminarily treated.

The saving of fuel which is reached by carrying the hot products from chamber M' to chamber M is very great, for the heat so transmitted can be utilized for maintaining the contents of the chamber M at red 130.

heat for a long period, such as twenty-four hours.

What I claim is:

1. In an apparatus for baking earthenware, an upwardly elongated integral refractory main wall structure, having a relatively elevated primary oven chamber therein and also a secondary oven chamber immediately below the primary chamber, a horizontal thin floor and ceiling structure between the two ovens, short vertical gas passages through said floor and ceiling structure, a series of furnaces uniformly distributed around the lower oven chamber and in the horizontal planes of the bottom part thereof, a series of furnaces uniformly distributed around the upper oven chamber and located in the horizontal planes of the bottom part thereof, the hot-gas inlet ducts from the upper furnaces to the upper part of the primary oven, the hot-gas inlet passages extending upward from the lower furnaces to the upper part of the secondary oven chamber, the bottom structure of the lower oven having vertical and horizontal gas escape passages, and the vertical escape flues in the main wall structure communicating with the passages in said bottom structure.
  2. In an apparatus for baking earthenware, an upwardly elongated integral refractory main wall structure, inclosing a relatively elevated primary oven chamber therein and a secondary oven chamber immediately below the primary oven, a thin horizontal floor and ceiling structure between the two oven chambers, short gas passages through said floor and ceiling structures, a series of furnaces in the said main wall structure, arranged in the horizontal planes of the bottom part of the upper oven chamber, a supplemental series of furnaces in the said main wall structure, arranged in the horizontal planes of the bottom part of the lower secondary oven chamber, a bottom structure below the lower secondary oven chamber, elongated vertical escape flues in the main wall structure, and escape passages in the said bottom structure of the lower oven communicating with said escape flues.
  3. In an apparatus for baking earthenware, a vertically elongated refractory main wall structure, inclosing three superposed ovens, viz: a primary central oven, a sec-
- ondary lower oven below the primary oven, 55 and a third upper oven above the primary oven, gas passages in the floor of the primary oven communicating with the lower secondary oven, furnaces for supplying hot gas to the upper parts of the primary and 60 the lower oven, respectively, and ducts for conducting gases to the third upper oven from either or both the two aforesaid ovens.
4. In an apparatus for heating earthenware and for similar purposes, the refractory wall inclosing the oven chamber, a relatively deep bottom structure for the chamber having a number of independent zig-zag gas ducts, apertures communicating with each of said ducts and with the lower part of the 70 chamber, and the escape ducts.
5. In an apparatus for heating earthenware and similar purposes, a vertical refractory wall inclosing a chamber and having inlets for gas near the upper part of the 75 chamber and a bottom structure formed of a relatively deep mass of refractory material provided with a series of tortuous passages, each having its several parts in substantially the same radial planes, and having supply 80 and exit passages communicating with vertical escape flues.
6. In a burning, calcining or heating apparatus, the combination of the first oven, a second oven above it, a third oven above 85 the second, the hot gas supplying apparatus arranged to deliver gas to the upper part of the second oven, the ducts arranged to take said gas from the second oven to the first and to withdraw it from the first and deliver 90 it to the third.
7. In a burning, calcining or heating apparatus, the first oven, the second oven above it, and the third oven above the second, communicating gas passages between the second 95 oven and the first, a gas passage between the second oven and the third adapted to be closed, and draft passages adapted to cause the passage of gas from the second oven to the first and from the bottom of the first to 100 the third oven.

In testimony whereof, I affix my signature, in presence of two witnesses.

GEORGE LITINSKY.
